UNITED STATES PATENT OFFICE.

LAUREL B. COLLINS, OF CHICAGO, ILLINOIS.

FOLDING CRATE.

1,329,376.

Specification of Letters Patent.

Patented Feb. 3, 1920.

Application filed July 20, 1917. Serial No. 181,789.

To all whom it may concern:

Be it known that I, LAUREL B. COLLINS, a citizen of the United States, and a resident of the city of Chicago, in the county of Cook and State of Illinois, have invented 5 certain new and useful Improvements in Folding Crates; and I do hereby declare that the following is a full, clear, and exact description of the same, reference being had to the accompanying drawings, and the numerals of reference marked thereon, which form a part of this specification.

This invention comprehends improvements in folding crates which are especially adapted 15 for confining poultry, and the primary object of the invention is to provide a crate of this nature, which shall be of strong and simple construction, and which may be quickly folded into a very compact form.

Another and more specific object of the invention is to provide a folding crate having 20 a bottom, end walls hinged thereto so as to fold thereagainst, side walls hinged so as to fold over the end walls, and top wall sections hinged to the side walls.

Another object of the invention is to provide a novel means for holding the crate in its folded position, said means including a 25 loop or staple carried by the bottom and a pin extending through said staple into engagement with the top wall sections.

With these and other objects in view as will become more apparent as the description proceeds, the invention consists in certain 35 novel features of construction, combination and arrangement of parts as will be hereinafter more fully described and claimed.

The invention (in a preferred form) is 40 illustrated in the drawings and hereinafter more fully described.

On the drawings:

Figure 1 is a top plan view of my improved crate.

Fig. 2 is an end elevation thereof.

Fig. 3 is a vertical longitudinal sectional view.

Fig. 4 is a transverse sectional view, showing the crate in its folded position.

As shown on the drawings:

5 designates the bottom of the crate, and 6 and 7, the end walls, which are secured to the bottom by means of hinges 8. Longitudinal flanges or spacing strips 9, are secured to the upper surface of the bottom adjacent the edges thereof, and have connected

thereto the side walls 10 and 11. These walls are connected to the spacing strips 9, by means of hinges 12, and are adapted to fold into planes parallel with the bottom 5, and 60 above the end walls when the latter are in their folded position. The free longitudinal edges of the side walls 10 and 11, carry the top wall sections 13 and 14, said sections being secured to the side walls by means of 65 the hinges 15.

To retain the crate in its folded position, as shown in Fig. 4, I provide a locking loop or staple 16, which is secured to the center of the bottom 5, and which projects upwardly between the side walls and top wall sections when in their folded position, to receive the locking rod or pin 17. The ends of the retaining loop 16, are extended through an opening formed in the bottom 75 5, and then bent upwardly against said bottom so as to securely retain the loop in its proper position. It will be noted that the loop lies in the center longitudinal plane of the crate. The bottom of the crate, the end 80 walls and side walls and the top wall sections are so proportioned as not to engage the loop 16, when the crate is in its folded position.

Each of the top wall sections is provided 85 with cleats 18, which form transverse grooves into which the upper edges of the end walls extend, thereby strengthening the crate. The top wall section 13, is provided with a removable panel 19, held in place by 90 the cross strips 20, said panel being for the purpose of allowing the poultry within the coop to be easily removed without entirely opening the top. The top wall sections are preferably retained in their operative positions by means of a hook 22, and headed pin 23.

From the foregoing description taken in connection with the accompanying drawings, it will be apparent that I have provided 100 a very simple and practical poultry crate which may be quickly and easily folded into a very compact form and locked in said position by a novel form of fastener.

I am aware that various details of construction may be varied through a wide range without departing from the principles of this invention, and I therefore do not purpose limiting the patent granted otherwise than necessitated by the prior art.

I claim as my invention:

1. In a folding crate, the combination of

a bottom section, folding end sections and folding side sections hinged at their lower edges to the said bottom section to fold inwardly onto the bottom section, a hinged 5 top section provided with cleats on the under surface adapted to engage the end sections of the crate, the said top section being reversely positioned when the crate is collapsed so that the said cleats are on the 10 upper surface of the said top section in the collapsed position, and means above the top section intermediate of but not projecting substantially above the upper surface of said cleats for locking the crate in the collapsed 15 condition.

2. In a folding crate, the combination of the bottom section, side and end sections hinged at their lower edges to the said bottom section and adapted to be folded there- 20 on, a folding top section suitably pivoted so that the under side thereof faces upwardly when the crate is folded, cleats on the top section adapted to engage the end walls of the crate in its expanded condition 25 and project above the crate in its folded condition, and means projecting above the folded top section intermediate of but not projecting substantially above the upper sur- 30 face of the said cleats for locking the crate in the folded position.

3. In a folding crate, the combination of the bottom section, inwardly folding side and end sections, a pair of outwardly folding top sections adapted to overlie the said 35 folding end and side sections, a locking member projecting between and above the folded top sections, said locking member be-

ing provided with an opening arranged transversely of the folded top sections, and a longitudinal locking member adapted to 40 be passed through the said opening transversely of the folded top section so as to engage both sections for locking the crate in its folded condition.

4. In a folding crate, the combination of 45 a bottom section, end and side sections adapted to be folded inwardly over the top, a folding top section adapted to fold over the folded end and side sections, a stationary locking member projecting from the 50 bottom of the crate for locking the crate in its folded condition and locking means on the folding top of the said crate adapted to lock the crate in its expanded condition independently of the means for locking the 55 crate in its folded condition.

5. In a folding crate, the combination of the bottom section, inwardly folding side and end sections, a pair of folding top sections adapted to overlie the said folding side 60 and end sections, cleats on top of each folded top section adapted to engage the end sections when the crate is extended, and locking means intermediate of but not projecting substantially above the upper sur- 65 face of said cleats engaging the upper surface of each folded top section.

In testimony whereof I have hereunto sub-
scribed my name in the presence of two sub-
scribing witnesses.

LAUREL B. COLLINS.
